US0D1106073S

(12) **United States Design Patent** (10) **Patent No.:** **US D1,106,073 S**
(45) **Date of Patent:** **** Dec. 16, 2025**

(54) **CONNECTOR**

(71) Applicant: **Japan Aviation Electronics Industry, Limited**, Tokyo (JP)

(72) Inventors: **Minoru Shinmyo**, Tokyo (JP); **Yuichi Uchiyama**, Tokyo (JP); **Osamu Takagi**, Tokyo (JP); **Masaki Ishiguro**, Tokyo (JP); **Junichi Miyamoto**, Tokyo (JP); **Takashi Tokunaga**, Tokyo (JP); **Tomoyuki Uchida**, Tokyo (JP); **Takuya Shiraishi**, Tokyo (JP); **Toshihiro Oka**, Tokyo (JP); **Shigeyasu Kitamura**, Tokyo (JP)

(73) Assignee: **Japan Aviation Electronics Industry, Limited**, Tokyo (JP)

(**) Term: **15 Years**

(21) Appl. No.: **29/929,466**

(22) Filed: **Feb. 22, 2024**

(30) **Foreign Application Priority Data**

Sep. 11, 2023 (JP) ..... 2023-018555 D

(51) **LOC (15) Cl.** **13-03**

(52) **U.S. Cl.**

(57) **CLAIM**

The ornamental design for a connector as shown and described.

DESCRIPTION

FIG. 1 is a front elevational view of a connector showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, top, and right side perspective view thereof;

FIG. 8 is a rear, bottom, and left side perspective view thereof;

FIG. 9 is a front, right, and bottom side perspective view thereof; and,

FIG. 10 is a rear, left, and top side perspective view thereof. The broken line showing of the connector is for the purpose of illustrating portions of the article and forms no part of the claimed design.

1 Claim, 9 Drawing Sheets
